TUBE

R. Harry Stone, Irvington, N. J., assignor to
Titeflex Metal Hose Co., a corporation of New
Jersey

Application May 7, 1929, Serial No. 361,039

4 Claims. (Cl. 138—51)

This invention relates to flexible corrugated seamed tubing in which substantially all of the flexibility is imparted by flexure of the sides of the corrugations. More particularly it relates to tubing formed of more than one helically disposed strip. Such strips may not have similar cross-sectional configuration.

It is an object of this invention to improve the construction and to render more durable tubes of this character.

Another object is to arrange this type of flexible tube so that it may be more readily made fluid tight by sealing the adjacent seams. A still further object is to arrange a tube with a groove or other depression along the seam in which may be located a wearing member which is particularly useful for preventing direct wear on the tube material from movement between the tube and a compression resisting covering outside said tube. Particularly where braided coverings are used directly in contact with flexible metal tubes, destructive wearing often takes place. With an independent wearing member this can be prevented and the wearing member be easily replaced after considerable use.

A further object is to produce a flexible metallic tube having a seam in which packing or sealing material may be introduced after the tube has been formed whereby different packings and sealings may be used, dependent upon the use to which the tube is put without necessitating complete construction of the tube for a particular purpose.

A still further object is to arrange a seamed flexible metallic tubing composed of two or more helically disposed strips in which one of the strips may be composed of thick material for rigidly securing the seam while another strip may be composed of thinner material but with greater flexibility.

Further and more definite objects will appear from the following specifications, claims and drawings in which:

Fig. 1 shows a tube with portions cut away to indicate a section, embodying my invention;

Figs. 2 to 7 inclusive show other modified sections useable according to this idea; and

Fig. 8 shows a further section indicating how my tube may be utilized in connection with a strain resistant covering.

Referring now more particularly to the drawings, the tube shown in Fig. 1 is composed of strips 1 and 2 secured together by means of seams 5 and 6, leaving a space therebetween indicated at 7. As shown, strip 1 is bent outwardly in relation to

the strip 2 and strip 2 is bent inwardly at the point of the seam. By this arrangement a very effective and compact tubing can be constructed. In order to more securely hold the parts together and aid in their tightness a packing or binding compound such as asbestos, shellac or soldering may be applied in the channel 7 as shown at 9, the term soldering including soft and hard soldering (the latter being often referred to as brazing) and welding. This may be applied in a liquid form and allowed to harden, the packing 9 more particularly designating shellac such as would be utilized in connection with a tube intended to conduct gasoline and like liquids.

The packing 11 may be composed of mineral or vegetable fibre with or without binding compounds as for instance a steam hose might be packed with asbestos fibre and a binding compound of white lead.

For heavy service and high pressure the joint shown in Fig. 4 could be reinforced with solder or brazing material 14 which not only makes a tight joint but also unites the edges of the flexible strip and locking strip rigidly in such a manner that seams will not break with the flexing or bending of the hose. It is thus apparent that with this type of tube construction that the joints may be made tight either in the process of manufacture or after the tube is manufactured. The tube may be manufactured without packing or equivalent material, and placed in stock to be withdrawn and properly packed for the particular kind of service desired without the expense of different supplies of tubing for each particular type of service.

Where greater flexibility is desired the pitch of the hose could be materially decreased by single lock seams as shown in Fig. 5. Here the outer strips 19 and 20 could be connected together with the inner strip 18 secured in the seams 16 and 17. It may be an advantage to make the locking strip 18 of thicker metal for the single lock seam shown in Fig. 5 in order that the flexibility may be confined to the outer strip 19 and 20 while the inner or locking strip may be depended upon to secure rigidly the joint. Packing, soldering or like material could be applied in the opening between the two seams 16 and 17.

A further variation could be utilized as shown in connection with Fig. 6 where the inner strip 22 is slightly beveled inwardly as at 23 providing a recess 24 in which packing or other material 25 could be applied more effectively. Packing in this type might be omitted and the rib 23 utilized to add flexibility to the tubing. If packing is ap-

plied it is obvious that it will be more securely anchored than would be possible with other modifications. In this construction the inner locking strip 22 might be constructed of lighter materials than the outer strip so as to increase flexibility.

Where heavy duty is required a triple lock seam as shown in Fig. 7 could be employed, flexibility being sacrificed to some extent and a seam is provided which would not require soldering between the adjacent seams, although solder could be applied as in the case of the previous joints as desired.

Heretofore in utilizing some types of flexible tubing in connection with braided coverings it has been found that the braid after a time cuts into the hose causing it to leak. With the type of hose shown in Fig. 2 after the joint is soldered or properly packed, a wire can be wound in the spiral groove as shown in Fig. 8 and the wear will be taken on the wire instead of the hose. The wire 28 being positioned between the seams 29 and 30 they will be securely maintained in the recess therebetween so that no friction occurs at that point, but any movement which takes place will occur between the braided covering 31 and the wire 28. If a great amount of wear takes place so that the braided covering 31 no longer sufficiently reenforces the tubing, a new wire 28 may be provided without affecting the operation of the tube and at a minimum of expense. The braided covering 31 is usually composed of interwoven wire and applied directly on the tubing in order to prevent internal expansion of the contents of the tube. Such a covering also prevents rotation of the ends of the tube one with respect to the other in such a way as to cause slipping in the joints. In order to maintain the contents of the tube invariably it is necessary to apply the braid directly to the surface of the tube so that no compressible material will come therebetween. By this construction considerable wear is removed from the surface and applied to a part which may be readily replaced.

It is thus apparent that a flexible tube has been disclosed in which a separate binding strip may be associated with the edges of adjacent convolutions of the main or outer strip. Both strips are of a trough-shaped cross-section of similar configuration on either side of the trough. The two strips thus joined together are arranged with a depression therebetween in which packing material or other binding substance might be applied after the tube is manufactured so that different portions of the same tube length might be utilized for different services without requiring that the tubes be separately mechanically constructed. By this arrangement a packing groove is provided between alternately folded portions or seams, which maintain the two strips in position, one with relation to the other, and the outer edges of each convolution has reversely folded portions providing this opening. By filling this opening with packing material not only are the seams rendered more nearly fluid tight but also they are maintained more nearly mechanically rigid. The two strips that compose the tubing each have a trough formation and one part may be of greater depth than the other or if desired may both have the same depth. In any event one of the strips is constructed of blank material which is narrower than the other strip, inasmuch as one strip is outside the other and therefore requires a wider strip. The use of the wearing member 28 may not only resist the

effect of wear of a braided covering but also may be used to maintain the joints or seams 29 and 30 more securely in place as well as prevent displacement from any packing material which may line between these seams.

It is not intended to be confined to the exact construction but considerable variation and modification is intended to be included without departing from the spirit and scope of the invention herein set forth. I desire to be limited only to the extent indicated in the following claims.

What I claim is:

1. A flexible tube formed of a helically disposed strip having a longitudinal fold or groove, the bottom of said groove being at the innermost wall of the completed tube, and a separate strip helically disposed between the adjacent edges of convolutions of said grooved strip and secured thereto by interfolding into fixed relation the edges of said separate strip with the outer edges of the said grooved strip; the sides of the groove in said grooved strip and the separate strip interfolded therewith forming an outwardly extending corrugation providing flexibility by bending in the corrugation, the outer edges of contiguous sides of adjacent convolutions of said grooved strip being spaced apart and said separate strip being located inwardly of the outermost edges of said grooved strip whereby a depressed channel or groove is formed in the outermost wall of the corrugation of the completed tube, a covering disposed about the tube and extending across spaces between corrugations and a separate wearing member lodged in the said depressed channel in the outermost wall of the corrugation.

2. A flexible tube formed of a helically disposed strip having a longitudinal fold or groove, the bottom of said groove being at the innermost wall of the completed tube, and a separate strip helically disposed between the adjacent edges of convolutions of said grooved strip and secured thereto by interfolding into fixed relation the edges of said separate strip with the outer edges of the said grooved strip, the sides of the groove in said grooved strip and the separate strip interfolded therewith forming an outwardly extending corrugation providing flexibility by bending in the corrugation, the outer edges of contiguous sides of adjacent convolutions of said grooved strip being spaced apart and said separate strip being located inwardly of the outermost edges of said grooved strip whereby a depressed channel or groove is formed in the outermost wall of the corrugation of the completed tube, the interfolded edges of said separate strip being bent outwardly of the tube and then toward each other longitudinally of the tube and the interfolded adjacent edges of the first mentioned strip being bent toward each other longitudinally of the strip then inwardly of the tube and then away from each other longitudinally of the tube.

3. A flexible tube formed of a helically disposed strip having a longitudinal fold or groove, the bottom of said groove being at the innermost wall of the completed tube, and a separate strip helically disposed between the adjacent edges of convolutions of said grooved strip and secured thereto by interfolding into fixed relation the edges of said separate strip with the outer edges of said grooved strip, the sides of the groove in said grooved strip and the separate strip interfolded therewith forming an outwardly extending corrugation providing flexibility by bending in the corrugation, the outer edges of contiguous

- sides of adjacent convolutions of said grooved strip being spaced apart and said separate strip being located inwardly of the outermost edges of said grooved strip whereby a depressed channel or groove is formed in the outermost wall of the corrugation of the completed tube, the thickness of said separate strip at the bottom of the channel being less than the depth of the channel outside of said separate strip and between the inter-folded joints. 4. A flexible tube formed of a helically disposed strip having a longitudinal fold or groove, the bottom of said groove being at the innermost wall of the completed tube, and a separate strip helically disposed between the adjacent edges of convolutions of said grooved strip and secured thereto by interfolding into fixed relation the edges of said separate strip with the outer edges of the said grooved strip, the sides of the groove in said grooved strip and the separate strip inter-folded therewith forming an outwardly extending corrugation providing flexibility by bending in the corrugation, the outer edges of contiguous sides of adjacent convolutions of said grooved strip being spaced apart and said separate strip being located inwardly of the outermost edges of said grooved strip whereby a depressed channel or groove is formed in the outermost wall of the corrugation of the completed tube, the thickness of said separate strip at the bottom of the channel being less than the depth of the channel outside of said separate strip and between the inter-folded joints, the said strips being soldered together in said channel. 5. A flexible tube formed of a helically disposed strip having a longitudinal fold or groove, the bottom of said groove being at the innermost wall of the completed tube, and a separate strip helically disposed between the adjacent edges of convolutions of said grooved strip and secured thereto by interfolding into fixed relation the edges of said separate strip with the outer edges of the said grooved strip, the sides of the groove in said grooved strip and the separate strip inter-folded therewith forming an outwardly extending corrugation providing flexibility by bending in the corrugation, the outer edges of contiguous sides of adjacent convolutions of said grooved strip being spaced apart and said separate strip being located inwardly of the outermost edges of said grooved strip whereby a depressed channel or groove is formed in the outermost wall of the corrugation of the completed tube, the thickness of said separate strip at the bottom of the channel being less than the depth of the channel outside of said separate strip and between the inter-folded joints, the said strips being soldered together in said channel. 10. A flexible tube formed of a helically disposed strip having a longitudinal fold or groove, the bottom of said groove being at the innermost wall of the completed tube, and a separate strip helically disposed between the adjacent edges of convolutions of said grooved strip and secured thereto by interfolding into fixed relation the edges of said separate strip with the outer edges of the said grooved strip, the sides of the groove in said grooved strip and the separate strip inter-folded therewith forming an outwardly extending corrugation providing flexibility by bending in the corrugation, the outer edges of contiguous sides of adjacent convolutions of said grooved strip being spaced apart and said separate strip being located inwardly of the outermost edges of said grooved strip whereby a depressed channel or groove is formed in the outermost wall of the corrugation of the completed tube, the thickness of said separate strip at the bottom of the channel being less than the depth of the channel outside of said separate strip and between the inter-folded joints, the said strips being soldered together in said channel. 15. A flexible tube formed of a helically disposed strip having a longitudinal fold or groove, the bottom of said groove being at the innermost wall of the completed tube, and a separate strip helically disposed between the adjacent edges of convolutions of said grooved strip and secured thereto by interfolding into fixed relation the edges of said separate strip with the outer edges of the said grooved strip, the sides of the groove in said grooved strip and the separate strip inter-folded therewith forming an outwardly extending corrugation providing flexibility by bending in the corrugation, the outer edges of contiguous sides of adjacent convolutions of said grooved strip being spaced apart and said separate strip being located inwardly of the outermost edges of said grooved strip whereby a depressed channel or groove is formed in the outermost wall of the corrugation of the completed tube, the thickness of said separate strip at the bottom of the channel being less than the depth of the channel outside of said separate strip and between the inter-folded joints, the said strips being soldered together in said channel.

R. HARRY STONE.
